ABSTRACT

A controller causes a notification device to provide a first alert in response to receipt of a first signal from a liquid level sensor. After the controller determines that a cartridge is located at a particular position in an installation case, the controller clears the first alert in response to receipt of a second signal from the liquid level sensor.

CROSS-REFERENCE TO RELATED APPLICATION

This application claims priority from Japanese Patent Application No. 2018-068761 filed on Mar. 30, 2018, the content of which is incorporated herein by reference in its entirety.

TECHNICAL FIELD

Aspects described herein relates to a liquid discharge apparatus.

BACKGROUND

A known inkjet printer includes a detachably attachable main tank, a sub tank for storing ink supplied from the main tank attached to the inkjet printer, and an image recording unit for recording an image by discharging ink stored in the sub tank. An internal space of the main tank and an internal space of the sub tank each communicate with outside air. Therefore, when the main tank is attached to the inkjet printer, ink moves such that a surface of ink stored in the main tank and a surface of ink stored in the sub tank become at the same level due to a hydraulic pressure difference between the internal space of the main tank and the internal space of the sub tank. Based on an ink remaining amount detected by a sensor having reached lower than a threshold, the inkjet printer displays, on a display, an empty indication indicating that the main tank needs to be replaced with another, and/or prohibits ink discharge through the image recording unit.

SUMMARY

In response to attachment of a main tank to the inkjet printer due to main tank replacement, ink may move from the attached main tank to the sub tank. Thus, the remaining amount of ink in the sub tank may increase. The inkjet printer may be therefore configured to, in response to attachment of a main tank to the inkjet printer due to the main tank replacement, cancel display of the empty indication on the display and/or clear the prohibition of ink discharge. Nevertheless, such an inkjet printer might not determine actually whether the sub tank stores enough ink supplied from the main tank until a signal outputted by the sensor changes. Thus, a problem may occur in such an inkjet printer if a newly-attached main tank stores only a slight amount of ink. For example, in a case where the inkjet printer cancels the display of the empty indication on the display in response to attachment of a main tank due to the main tank replacement, the sub tank may remain in an empty state although the inkjet printer clears the empty indication on the display. In another case where the inkjet printer clears the prohibition of ink discharge in response to attachment of a main tank due to the main tank replacement, the inkjet printer may perform printing although the sub tank is still in the empty state (i.e., the sub tank does not store a sufficient amount of ink). This may cause intrusion of air into an ink channel that extends from the sub tank to the image recording unit.

Accordingly, some embodiments of the disclosure provide for a liquid discharge apparatus that may clear an alert after determining that a surface level of liquid in a tank has

reached a predetermined level through liquid movement from a cartridge to the tank after cartridge replacement.

A liquid discharge apparatus includes an installation case, a tank, a head, a liquid level sensor, a notification device, and a controller. The installation case may be configured to accommodate a cartridge including a cartridge channel and a cartridge chamber. The tank may include a chamber. The tank may further include a first channel, a second channel, and a third channel. The first channel may include one end 10 in fluid communication with an outside of the tank and an opposite end in fluid communication with the chamber. The second channel may include one end positioned below the first channel and in fluid communication with the chamber; and. The third channel may include one end in fluid communication with the chamber and the other end communicated with the outside of the tank. The head may be in fluid communication with an opposite end of the second channel from the one end. The cartridge chamber may be in fluid communication with the chamber of the tank via at least one 15 of the cartridge channel and the first channel while the cartridge is located at a particular position in the installation case. The controller may be configured to receive a first signal from the liquid level sensor, wherein the first signal is outputted from the liquid level sensor if a surface level of liquid in the chamber is lower than a predetermined level; in response to the receipt of the first signal, cause the notification device to provide a first alert; determine whether the cartridge is located at the particular position in the installation case; receive a second signal from the liquid level sensor, wherein the second signal is outputted if the surface 20 level of liquid in the chamber is higher than or equal to the predetermined level; and in response to the receipt of the second signal from the liquid level sensor after determining that the cartridge is located at the particular position in the installation case, clear the first alert.

The liquid discharge apparatus may further include the cartridge.

According to one or more aspects of the disclosure, the controller may be configured to, in response to the receipt of the second signal from the liquid level sensor after determining that the cartridge is located at the particular position in the installation case, clear the first alert. In other words, the first alert may be cleared after a user recognizes that the liquid amount in the tank has become sufficient by liquid 40 flow from the cartridge to the tank. Such a configuration may thus avoid clearance of the first alert indicating empty notification before the liquid amount in the tank becomes sufficient by liquid flow from the cartridge to the tank.

In the liquid discharge apparatus, the controller may be 50 configured to receive a discharge instruction for discharging liquid through the head; determine a count value corresponding to a liquid amount based on the discharge instruction that has been received after receiving the first signal; determine whether the count value has reached a threshold; 55 and based on determining that the count value has reached the threshold, cause the notification device to provide the first alert.

In the liquid discharge apparatus, the controller may be 60 configured to: in response to the receipt of the first signal, prohibit liquid discharge through the head; and in response to the receipt of the second signal from the liquid level sensor after determining that the cartridge is located at the particular position in the installation case, clear the prohibition of liquid discharge through the head.

According to one or more aspects of the disclosure, the controller may be configured to, in response to the receipt of the second signal from the liquid level sensor after deter-

mining that the cartridge is located at the particular position in the installation case, clear the prohibition of liquid discharge. In other words, the prohibition of liquid discharge may be cleared after a user recognizes that the liquid amount in the tank has become sufficient by liquid flow from the cartridge to the tank. Such a configuration may thus reduce intrusion of air into a liquid channel that may extend from the tank to the head.

In the liquid discharge apparatus, the controller may be configured to, in response to absence of the second signal from the liquid level sensor before the controller determines that an elapsed time has exceeded a specified time since the controller determined that the cartridge is located at the particular position in the installation case, cause the notification device to provide a second alert.

According to one or more aspects of the disclosure, the controller may be configured to, in response to not determining, within the specified time, that the liquid amount in the tank has become sufficient by supply of liquid from the cartridge to the tank, cause the warning device to provide the second alert. For example, the cartridge newly accommodated in the installation case may store relatively small amount of liquid and thus the liquid amount in the tank might not become sufficient by liquid flow from the cartridge to the tank. In this case, such a configuration may enable a user to inform that liquid amount in the tank has not become sufficient by liquid flow from the cartridge to the tank.

In the liquid discharge apparatus, the controller may be configured to: based on the determination that the cartridge is located at the particular position in the installation case, cause the notification device to provide a third alert; and in response to the receipt of the second signal from the liquid level sensor being absent before the controller determines that an elapsed time has exceeded a specified time since the controller determined that the cartridge is located at the particular position in the installation case has been completed, cause the notification device to provide a fourth alert.

According to one or more aspects of the disclosure, the controller may be configured to, in response to determining that the cartridge is located at the particular position in the installation case, cause the notification device to provide the third alert, and in response to not determining, within the specified time, that the liquid amount in the tank has become sufficient by liquid flow from the cartridge to the tank, cause the notification device to provide the fourth alert. For example, the cartridge newly accommodated the installation case may store relatively small amount of liquid. In this case, after the controller causes the notification device to provide a user with a notification that the liquid is being supplied to the tank from the cartridge, the liquid amount in the tank might not have become sufficient by liquid flow from the cartridge to the tank. If such a situation happens, the above configuration may enable a user to inform that the liquid amount in the tank has not become sufficient by liquid flow from the cartridge to the tank.

The liquid discharge apparatus may further include an interface. In the liquid discharge apparatus, the installation case may be configured to accommodate one of different types of cartridges. In one example, the controller may be configured to, based on the determination that the one of the different types of cartridges is located at the particular position in the installation case, read cartridge information indicating a type of the accommodated cartridge, from a memory of the accommodated cartridge through the interface; and determine whether the elapsed time has exceeded the specified time, the specified time being determined based on the read cartridge information.

In another example, the controller may be configured to, based on the determination that the one of the different types of cartridge is located at the particular position in the installation case, read cartridge information indicating viscosity of liquid in the cartridge chamber, from a memory of the accommodated cartridge through the interface; and determine whether the elapsed time has exceeded the specified time, the specified time being determined based on the read cartridge information.

10 In still another example, the controller may be configured to, based on the determination that the one of the different types of cartridge is located at the particular position in the installation case, read cartridge information indicating a surface level of liquid in the cartridge chamber, from a memory of the accommodated cartridge through the interface; and determine whether the elapsed time has exceeded the specified time, the specified time being determined based on the read cartridge information.

15 In yet another example, the controller may be configured to, based on the determination that the one of the different types of cartridges is located at the particular position in the installation case, read cartridge information indicating a channel resistance of the accommodated cartridge, from a memory of the accommodated cartridge through the interface; and determine whether the elapsed time has exceeded the specified time, the specified time being determined based on the read cartridge information.

20 The time required for liquid flow from the cartridge to the tank may vary according to a liquid flow speed from the cartridge to the tank. The liquid flow speed may also vary according to, for example, a cross-sectional area of the cartridge chamber, the surface level of liquid in the cartridge chamber, and/or liquid viscosity. According to one or more aspects of the disclosure, in the determination as to whether 25 the elapsed time has exceeded the specified time, the controller may use an appropriate specified time based on the cartridge information read from the cartridge memory of the accommodated cartridge. Such a configuration may thus enable provision of the empty notification at an appropriate 30 timing in a case where the liquid amount in the tank has not become sufficient by liquid flow from the cartridge to the tank.

35 The liquid discharge apparatus may further include a temperature sensor. In the liquid discharge apparatus, the controller may be configured to receive a signal from the temperature sensor, the signal outputted responsive to ambient temperature; and determine whether the elapsed time has exceeded the specified time, the specified time being determined based on the signal received from the temperature sensor.

40 Temperature change may cause change in the liquid viscosity, thereby causing change in the liquid flow speed from the cartridge to the tank. This may further cause change in the time required for the liquid flow from the cartridge to the tank. According to one or more aspects of the disclosure, in the determination as to whether the elapsed time has exceeded the specified time, the controller may use an appropriate specified time based on the signal outputted by the temperature sensor. Such a configuration may thus enable provision of the empty notification at an appropriate 45 timing in a case where the liquid amount in the tank has not become sufficient by supply of liquid from the cartridge to the tank.

50 Another liquid discharge apparatus may include an installation case, a tank, a head, a liquid level sensor, and a controller. The installation case may be configured to accommodate a cartridge including a cartridge channel and

a cartridge chamber. The tank may include a chamber. The tank may further include a first channel, a second channel, and the third channel. The first channel may include one end in fluid communication with an outside of the tank and an opposite end in fluid communication with the chamber. The second channel may include one end positioned below the first channel and in fluid communication with the chamber. The third channel may include one end in fluid communication with the chamber and the other end communicated with the outside of the tank. The head may be in fluid communication with an opposite end of the second channel from the one end. The cartridge chamber may be in fluid communication with the chamber of the tank via at least one of the cartridge channel and the first channel while the cartridge is located at a particular position in the installation case. The controller may be configured to receive a first signal from the liquid level sensor, wherein the first signal is outputted from the liquid level sensor if a surface level of liquid in the chamber is lower than a predetermined level; in response to the receipt of the first signal, prohibit liquid discharge through the head; determine whether the cartridge is located at the particular position in the installation case; receive a second signal from the liquid level sensor, wherein the second signal is outputted if the surface level of liquid in the chamber is higher than or equal to the predetermined level; and in response to the receipt of the second signal from the liquid level sensor after determining that the cartridge is located at the particular position in the installation case, allow the liquid discharge through the head.

The liquid discharge apparatus may further include a cartridge.

According to one or more aspects of the disclosure, the controller may be configured to, in response to the receipt of the second signal from the liquid level sensor after determining that the cartridge is located at the particular position in the installation case, allow the liquid discharge through the head. In other words, the liquid discharge may be allowed after a user recognizes that the liquid amount in the tank has become sufficient by liquid flow from the cartridge to the tank. Such a configuration may thus reduce intrusion of air into a liquid channel that may extend from the tank to the head.

The liquid discharge apparatus may further include a notification device. In such a liquid discharge apparatus, the controller may be configured to in response to the receipt of the first signal, cause the notification device to provide a first alert; and in response to the receipt of the second signal from the liquid level sensor after determining that the cartridge is located at the particular position in the installation case, clear the first alert.

According to one or more aspects of the disclosure, the controller may be configured to, in response to the receipt of the second signal from the liquid level sensor after determining that the cartridge is located at the particular position in the installation case, clear the first alert. In other words, the first alert may be cleared after a user recognizes that the liquid amount in the tank has become sufficient by liquid flow from the cartridge to the tank. Such a configuration may thus avoid clearance of the first alert indicating empty notification before the liquid amount in the tank becomes sufficient by liquid flow from the cartridge to the tank.

In the liquid discharge apparatus, the controller may be configured to, based on the determination that the cartridge is located at the particular position in the installation case, prohibit the liquid discharge through the head.

BRIEF DESCRIPTION OF THE DRAWINGS

FIG. 1A is an appearance perspective view of a printer in an illustrative embodiment according to one or more aspects of the disclosure, wherein a cover is located at a covering position.

FIG. 1B is an appearance perspective view of the printer in the illustrative embodiment according to one or more aspects of the disclosure, wherein the cover is located at an uncovering position.

FIG. 2 is a schematic cross-sectional view illustrating an internal configuration of the printer in the illustrative embodiment according to one or more aspects of the disclosure.

FIG. 3 is a cross-sectional view of an installation case in the illustrative embodiment according to one or more aspects of the disclosure.

FIG. 4A is a front perspective view of a cartridge in the illustrative embodiment according to one or more aspects of the disclosure.

FIG. 4B is a cross-sectional view of the cartridge in the illustrative embodiment according to one or more aspects of the disclosure.

FIG. 5 is a cross sectional view of the cartridge fully attached to the installation case in the illustrative embodiment according to one or more aspects of the disclosure.

FIG. 6 is a block diagram of the printer in the illustrative embodiment according to one or more aspects of the disclosure.

FIG. 7 is a flowchart of image recording processing in the illustrative embodiment according to one or more aspects of the disclosure.

FIG. 8 is a flowchart of count processing in the illustrative embodiment according to one or more aspects of the disclosure.

FIG. 9A illustrates an example S_Empty notification screen in the illustrative embodiment according to one or more aspects of the disclosure.

FIG. 9B illustrates an example ink refilling notification screen in the illustrative embodiment according to one or more aspects of the disclosure.

FIG. 9C illustrates an example C_Empty notification screen in the illustrative embodiment according to one or more aspects of the disclosure.

DETAILED DESCRIPTION

Hereinafter, an illustrative embodiment will be described. The illustrative embodiment described below is merely an example. Various changes, arrangements and modifications may be applied therein without departing from the spirit and scope of the invention. A top-bottom direction 7 may be defined with reference to an orientation of a printer 10 that may be disposed in an orientation in which it may be intended to be used with being placed on a horizontal surface. A side of the printer 10, in which an opening 13 may be defined, may be defined as the front of the printer 10. A front-rear direction 8 may be defined with reference to the front of the printer 10. A right-left direction 9 may be defined with respect to the printer 10 as viewed from the front of the printer 10. In the illustrative embodiment, the top-bottom direction 7 corresponds to the vertical direction and the front-rear direction 8 and the right-left direction 9 each correspond to the horizontal direction when the printer 10 is disposed in the used orientation. The front-rear direction 8 and the right-left direction 9 are orthogonal to each other.

Overall Configuration of Printer 10

The printer 10 is an example of a liquid discharge apparatus that records an image onto a sheet using an inkjet recording method. The printer 10 includes a housing 14 having a rectangular parallelepiped shape. In other embodiments, for example, the printer 10 may be a multifunction device having multiple functions, such as a facsimile transmission/reception function, a scanning function, and a copying function.

As illustrated in FIGS. 1 and 2, the printer 10 further includes a feed tray 15, a feed roller 23, conveying rollers 25, a head 21, a platen 26, output rollers 27, an output tray 16, an installation case 150, and one or more tubes 32. The head 21 has a plurality of nozzles 29. The platen 26 is disposed facing the head 21. The installation case 150 is configured such that one or more cartridges 200 are attached to and detached from the installation case 150. The tube 32 provides communication between the head 21 and the cartridge 200.

The printer 10 causes the feed roller 23 and the conveying rollers 25 to be driven to convey a sheet onto the platen 26 from the feed tray 15. The printer 10 then causes the head 21 to eject ink, which is supplied from the cartridge 200 attached to the installation case 150 through the tube 32, through appropriate ones of the nozzles 29. Thus, the ejected ink droplets land on the sheet supported by the platen 26 and an image is recorded on the sheet. Thereafter, the printer 10 causes the output rollers 27 to be driven to output the sheet on which the image has been recorded, onto the output tray 16.

More specifically, the head 21 may be mounted on a carriage that reciprocates in a main scanning direction intersecting a sheet conveyance direction in which the conveying rollers 25 convey a sheet. In such a case, the printer 10 may cause the head 21 to eject ink through appropriate ones of the nozzles 29 while moving the carriage from one side to the other side with respect to the main scanning direction. Thus, a portion of the image may be recorded on a portion of the sheet facing the head 21. Thereafter, the printer 10 may cause the conveying rollers 25 to convey the sheet such that another portion of the sheet which is subjected to the next recording faces the head 21. By repeating recording and conveyance, the entire image may be recorded on the sheet.

In the illustrative embodiment, ink discharge from the nozzles 29 of the head 21 during image recording is referred to as "ejection". Nevertheless, ink discharge from the nozzles 29 of the head 21 during purging is not referred to as "ejection", but "ejection" is included in a concept of "discharge".

Temperature Sensor 89

The printer 10 further includes a temperature sensor 89 (refer to FIG. 6) in the housing 14. The temperature sensor 89 enables a controller 130 to detect temperature in the housing 14. The temperature sensor 89 is configured to output different signals depending on ambient temperatures. The temperature in the housing 14 may be substantially equal to the temperature in the installation case 150. The controller 130 is thus configured to detect the temperature in the installation case 150 indirectly via the temperature sensor 89.

Cover 87

As illustrated in FIGS. 1A and 1B, the housing 14 has an opening 85 in its front surface 14A. The opening 85 is located at a right end portion of the housing 14 in the right-left direction 9. The housing 14 further includes a cover 87. The cover 87 is pivotable between a covering

position at which the cover 87 closes the opening 85 (e.g., a position of the cover 87 in FIG. 1A) and an uncovering position at which the cover 87 exposes the opening 85 (e.g., a position of the cover 87 in FIG. 1B). The cover 87 is supported by a lower end portion of the housing 14 in the top-bottom direction 9 so as to be pivotable on an axis extending along the right-left direction 9. The housing 14 has an accommodating space 86 therein. The accommodating space 86 extends toward the rear from the opening 85 in the housing 14. The installation case 150 is disposed in the accommodating space 86.

Cover Sensor 88

The printer 10 further includes a cover sensor 88 (refer to FIG. 6). In one example, the cover sensor 88 may be a mechanical sensor such as a switch to and from which the cover 87 contacts and separates. In another example, the cover sensor 88 may be an optical sensor in which light may be blocked or unblocked in accordance with the position of the cover 87. The cover sensor 88 is configured to output a signal to the controller 130 in response to the position of the cover 87. More specifically, for example, the cover sensor 88 is configured to, in response to the cover 87 located at the covering position, output a low level signal to the controller 130. On the other hand, the cover sensor 88 is configured to, in response to the cover 87 not located at the covering position, output a high level signal to the controller 130. In other words, the cover sensor 88 is configured to, when the cover 87 is located at the uncovering position, output a high level signal to the controller 130.

Installation Case 150

As illustrated in FIG. 3, the installation case 150 includes at least one each of a contact 152, a rod 153, an installation sensor 154, a liquid level sensor 155, and a lock pin 156. The installation case 150 is configured to accommodate four cartridges 200 corresponding to respective colors, e.g., black, cyan, magenta, and yellow. That is, the installation case 150 includes four each of the contact 152, the rod 153, the installation sensor 154, and the liquid level sensor 155. The number of cartridges 200 that the installation case 150 can accommodate therein is not limited to four, but may be one or five or more.

The installation case 150 has a box shape having an internal space for accommodating the cartridges 200. The internal space of the installation case 150 is defined by an upper wall defining an upper end of the internal space, a lower wall defining a lower end of the internal space, a rear wall defining a rear end of the internal space in the front-rear direction 8, and side walls defining right and left ends of the internal space in the right-left direction 9. The rear wall of the installation case 150 faces the opening 85. That is, when the cover 87 is located at the uncovering position, the opening 85 allows the internal space of the installation case 150 to be exposed to the outside of the printer 10.

Each of the cartridges 200 may be inserted into and detached from the installation case 150 through the opening 85 of the housing 14. More specifically, for example, when each of the cartridge 200 is attached to the installation case 150, each of the cartridges 200 enters the installation case 150 through the opening 85 by moving rearward in the front-rear direction 8. When each of the cartridge 200 is detached from the installation case 150, each of the cartridges 200 exits from the installation case 150 through the opening 85 by moving frontward in the front-rear direction 8.

Contacts 152

The contacts 152 are disposed at the upper wall of the installation case 150. The contacts 152 protrude downward

toward the internal space of the installation case 150 from the upper wall of the installation case 150. Each of the contacts 152 is disposed so as to contact a plurality of electrodes 248 of a corresponding one of the cartridges 200 in a state where each of the cartridges 200 is fully attached to the installation case 150. Each of the contacts 152 has conductivity and is elastically deformable in the top-bottom direction 7. Each of the contacts 152 is electrically connected to the controller 130.

Rods 153

The rods 153 protrude frontward from the rear wall of the installation case 150. The rods 153 are disposed above joints 180 at the rear wall of the installation case 150. Each of the rods 153 is configured to, during attachment of each of the cartridges 200 to the installation case 150, enter a ventilation valve chamber 214 via a ventilation opening 221 of a corresponding one of the cartridges 200. In response to entry of the rod 153 into the ventilation valve chamber 214, the ventilation valve chamber 214 becomes communicated with outside air.

Installation Sensors 154

The installation sensors 154 are disposed at the upper wall of the installation case 150. Each of the installation sensors 154 enables the controller 130 to determine whether a corresponding one of the cartridges 200 is being fully attached to the installation case 150, i.e., to determine whether a corresponding one of the cartridge is located at a particular position. Each of the installation sensors 154 includes a light emitter and a light receiver that are spaced apart from each other in the right-left direction 9. In a state where a cartridge 200 is attached to the installation case 150, a light blocking rib 245 of the cartridge 200 is located between a light emitter and a light receiver of a corresponding installation sensor 154. In other words, in such a state, the light emitter and the light receiver of the installation sensor 154 face each other while sandwiching the light blocking rib 245 of the cartridge 200 fully attached to the installation case 150.

Each of the installation sensors 154 is configured to output unique signals (in FIG. 7, referred to as an “installation signal”) depending on whether the light receiver has received light emitted from the light emitter in the right-left direction 9. For example, each of the installation sensors 154 is configured to, in response to a detection that intensity of light received by the light receiver is less than a threshold, output a low level signal to the controller 130. On the other hand, each of the installation sensors 154 is configured to, in a detection that intensity of light received by the light receiver is higher than or equal to the threshold, output a high level signal to the controller 130. The high level signal, e.g., 3V (three volts), has a higher signal strength than the low level signal, e.g., 0V (zero volt).

Liquid Level Sensors 155

Each of the liquid level sensors 155 enables the controller 130 to determine whether a detection portion 194 of an actuator 190 is located at a detection position. Each of the liquid level sensors 155 includes a light emitter and a light receiver that are spaced apart from each other in the right-left direction 9. When the detection portion 194 is located at the detection position, the light emitter and the light receiver of the liquid level sensor 155 face each other while sandwiching the detection portion 194. Each of the liquid level sensors 155 is configured to output unique signals (in FIG. 7, referred to as a “liquid level signal”) depending on whether the light receiver has received light emitted from the light emitter. For example, each of the liquid level sensors 155 is configured to, in response to a detection that

intensity of light received by the light receiver is less than a threshold, output a low level signal to the controller 130. On the other hand, each of the liquid level sensors 155 is configured to, in response to a detection that intensity of light received by the light receiver is higher than or equal to the threshold, output a high level signal to the controller 130. The high level signal, e.g., 3V (three volts), has a higher signal strength than the low level signal, e.g., 0V (zero volt). The high level signal is an example of a first signal, and the low level signal is an example of a second signal.

Lock Pin 156

The lock pin 156 is disposed in the internal space of the installation case 150. The lock pin 156 is located at an upper end portion of the installation case 150 and close to the opening 85. The lock pin 156 has a bar shape extending in the right-left direction 9. Both ends of the lock pin 156 in the right-left direction 9 are fastened to the side walls of the installation case 150. The lock pin 156 extends in the right-left direction 9 throughout all of four spaces capable of accommodating the respective four cartridges 200. The lock pin 156 is configured to retain each of the cartridges 200, which are fully attached to the installation case 150, at the particular position (refer to FIG. 5). In a state where each of the cartridges 200 is fully attached to the installation case 150, each of the cartridges 200 is engaged with the lock pin 156.

Tanks 160

The printer 10 further includes four tanks 160, which are provided for the respective cartridges 200. The tanks 160 are disposed further to the rear than the rear wall of the installation case 150. All of the tanks 160 have the same or similar configuration, and therefore, one of the tanks 160 will be described in detail. As illustrated in FIG. 3, the tank 160 is defined by an upper wall 161, a lower wall 163, a rear wall 164, and side walls. The front wall 162 includes a plurality of walls that are located at different positions with respect to the front-rear direction 8. The tank 160 has a liquid chamber 171 therein. The liquid chamber 171 is an example of a second liquid chamber.

Of the walls constituting the tank 160, at least the wall facing a corresponding liquid level sensor 155 is translucent or transparent to light. Thus, light emitted by the liquid level sensor 155 may pass through the wall that faces the liquid level sensor 155. A film may constitute at least a portion of the rear wall 164. In such a case, the film may have melted and stuck to end faces of the upper wall 161, the lower wall 163, and the side walls. The side walls of the tank 160 may be shared with the installation case 150 or may be provided separately from the side walls of the installation case 150. The tanks 160 adjacent to each other in the right-left direction 9 are partitioned by respective partition walls.

The liquid chamber 171 communicates with an ink channel via an outlet 174. The outlet 174 has a lower edge that is defined by the lower wall 163 defining the lower end of the liquid chamber 171. The outlet 174 is located below the joint 180 (more specifically, for example, a lower edge of a through hole 184). The ink channel communicating with the outlet 174 communicates with a corresponding tube 32 (refer to FIG. 2). Thus, the liquid chamber 171 communicates with the head 21 via the outlet 174, the ink channel, and the tube 32. That is, ink stored in the liquid chamber 171 is supplied to the head 21 via the outlet 174, the ink channel, and the tube 32. The ink channel and the tube 32 communicating with the outlet 174 is an example of a channel whose one end (e.g., the outlet 174) communicates with the liquid chamber 171 and whose other end 33 (refer to FIG. 2) communicates with the head 21.

11

The liquid chamber 171 communicates with air via a ventilation chamber 175. More specifically, for example, the ventilation chamber 175 communicates with the liquid chamber 171 via a through hole 176 that penetrates the front wall 162 of the tank 160. The ventilation chamber 175 communicates with the outside of the printer 10 via a ventilation port 177 and a tube connected to the ventilation port 177. That is, the ventilation chamber 175 is an example of a channel whose one end (e.g., the through hole 176) communicates with the liquid chamber 171 and whose other end (e.g., the ventilation port 177) communicates with the outside of the printer 10. The ventilation chamber 175 communicates with outside air via the ventilation port 177 and the tube.

Joints 180

As illustrated in FIG. 3, each of the joints 180 (one of which is illustrated in FIG. 3) includes a needle 181 and a guide 182. The needle 181 may be a hollow cylinder having a channel therein. The needle 181 protrudes frontward from the front wall 162 defining the liquid chamber 171. The needle 181 has an opening 183 at its protruding end. An internal space of the needle 181 communicates with the liquid chamber 171 via the through hole 184 that penetrates the front wall 162 of the tank 160. That is, the needle 181 is an example of a channel whose one end (e.g., the opening 183) communicates with the outside of the tank 160 and whose other end (e.g., the through hole 184) communicates with the liquid chamber 171. The guide 182 may be a hollow cylindrical member that surrounds the needle 181. The guide 182 protrudes frontward from the front wall 162 and has an opening at its protruding end.

In the internal space of the needle 181, a valve 185 and a coil spring 186 are disposed. The valve 185 is movable in the front-rear direction 8 between a closing position and an open position in the internal space of the needle 181. When the valve 185 is located at the closing position, the valve 185 closes the opening 183. When the valve 185 is located at the open position, the valve 185 opens the opening 183. The coil spring 186 urges the valve 185 in a direction in which the coil spring 186 moves the valve 185 from the open position to the closing position, i.e., toward the front.

Actuators 190

Each of the actuators 190 is disposed in a corresponding one of the liquid chambers 171. The actuator 190 is supported by a support member disposed in the liquid chamber 171 so as to be pivotable in a direction of an arrow 198 and in a direction of an arrow 199. The actuator 190 is pivotable between a position indicated by a solid line and a position indicated by a dashed line in FIG. 3. The actuator 190 is restricted in its further movement in the direction of the arrow 198 from the position indicated by the solid line by a stopper (e.g., one of inner walls of the liquid chamber 171). The actuator 190 includes a float 191, a shaft 192, an arm 193, and the detection portion 194.

The float 191 may be made of material having a lower specific gravity than ink stored in the liquid chamber 171. The shaft 192 protrudes from right and left surfaces of the float 191 in the right-left direction 9. The shaft 192 is engaged with holes of the support member by insertion. Thus, the actuator 190 is supported by the support member so as to be pivotable on the shaft 192. The arm 193 extends substantially upward from the float 191. The detection portion 194 is disposed at a protruding end of the arm 193. The detection portion 194 has a plate shape extending in both the top-bottom direction 7 and the front-rear direction 8. The detection portion 194 may be made of material that

12

may block light outputted by the light emitter of the liquid level sensor 155 or have a color that may block the light.

When a surface level of ink stored in the liquid chamber 171 is higher than or equal to a predetermined level P, the actuator 190 that has moved in the direction of the arrow 198 due to a buoyant force of the float 191 is retained at the detection position (indicated by the solid line in FIG. 3) by the stopper (this state is an example of a first state). When the surface level of ink stored in the liquid chamber 171 is lower than the predetermined level P, the actuator 190 moves in the direction of the arrow 199 with the ink level lowering. Thus, the detection portion 194 moves to stop at a position different from the detection position (this state is an example of a second state). That is, the detection portion 194 moves correspondingly to an amount of ink remaining in the liquid chamber 171.

The predetermined level P may be the same level as an axis of the needle 181 in the top-bottom direction 7 and the center of an ink supply port 234. The predetermined level P is indicated by an imaginary line extending in the horizontal direction in the drawings. Nevertheless, the predetermined level P is not limited to the specific example but may be any level unless being located higher than the outlet 174 in the top-bottom direction 7. In one example, the predetermined level P may be the same level as an upper edge or a lower edge of the internal space of the needle 181. In another example, the predetermined level P may be the same level as an upper edge or a lower edge of the ink supply port 234.

When the surface level of ink stored in the liquid chamber 171 is higher than or equal to the predetermined level P, the detection portion 194 blocks light outputted from the light emitter of the liquid level sensor 155. Thus, the light outputted from the light emitter does not reach the light receiver and the liquid level sensor 155 outputs a low level signal to the controller 130. When the surface level of ink stored in the liquid chamber 171 is lower than the predetermined level P, the detection portion 194 does not block light outputted from the light emitter of the liquid level sensor 155. Thus, the light outputted from the light emitter reaches the light receiver and the liquid level sensor 155 outputs a high level signal to the controller 130. That is, the controller 130 is capable of determining, based on a type of a signal outputted by the liquid level sensor 155, whether the surface level of ink stored in the liquid chamber 171 is higher than or equal to the predetermined level P.

Cartridges 200

All of the cartridges 200 have the same or similar configuration, and therefore, the description will be provided with respect to one of the cartridges 200. The cartridge 200 may be a container having a liquid chamber 210 (refer to FIG. 2). The liquid chamber 210 is configured to store ink therein. Ink is an example of liquid. The liquid chamber 210 is defined by walls made of, for example, resin or plastic. As illustrated in FIG. 4A, the cartridge 200 has greater dimensions in the top-bottom direction 7 and in the front-rear direction 8 than a dimension in the right-left direction 9. In one example, the cartridges 200 storing respective different colors of ink may have the same external shape. In another example, the cartridges 200 storing respective different colors of ink may have different external shapes. At least one or more of the walls of the cartridge 200 is transparent or translucent to light. This configuration may therefore enable a user to recognize the amount or surface level of ink stored in the liquid chamber 210 of the cartridge 200.

The cartridge 200 includes a housing 201 and a supply tube 230. The housing 201 includes a rear wall 202, a front wall 203, an upper wall 204, a lower wall 205, and side walls

206 and 207. The rear wall 202 includes a plurality of walls that are located at different positions in the front-rear direction 8. The upper wall 204 includes a plurality of walls that are located at different positions in the top-bottom direction 7. The lower wall 205 includes a plurality of walls that are located at different positions in the top-bottom direction 7.

As illustrated in FIG. 4B, the cartridge 200 includes the liquid chamber 210, an ink valve chamber 213, and the ventilation valve chamber 214. The liquid chamber 210 includes an upper liquid chamber 211 and a lower liquid chamber 212. The upper liquid chamber 211, the lower liquid chamber 212, and the ventilation valve chamber 214 may be internal spaces of the housing 210. The ink valve chamber 213 is an internal space of the supply tube 230. The liquid chamber 210 stores ink therein. The ventilation valve chamber 214 enables the liquid chamber 210 to communicate with the outside of the cartridge 200. The liquid chamber 210 is an example of a first liquid chamber.

A partition wall 215 (an example of a wall) is disposed for partitioning the inside of the housing 201. The upper liquid chamber 211 and the lower liquid chamber 212 of the liquid chamber 210 are partitioned by the partition wall 215 so as to be located one above the other in the top-bottom direction 7. The upper liquid chamber 211 and the lower liquid chamber 212 communicate with each other via a through hole 216 defined in the partition wall 215. Another partition wall 217 is disposed for further partitioning the inside of the housing 201. The upper liquid chamber 211 and the ventilation valve chamber 214 are partitioned by the partition wall 217 so as to be located one above the other in the top-bottom direction 7. The partition wall 215 has an upper surface 215U (an example of a first surface) defining a portion of the upper liquid chamber 211. The partition wall 215 has a lower surface 215L (an example of a second surface) defining a portion of the lower liquid chamber 212. The upper liquid chamber 211 and the ventilation valve chamber 214 communicate with each other via a through hole 218 defined in the partition wall 217. The ink valve chamber 213 communicates with a lower end of the lower liquid chamber 212 via a through hole 219.

The ventilation valve chamber 214 communicates with the outside of the cartridge 200 via the ventilation opening 221 defined in the rear wall 202 at an upper portion of the cartridge 200. That is, the ventilation valve chamber 214 is an example of a channel whose one end (e.g., the through hole 218) communicates with the liquid chamber 210 and whose other end (e.g., the ventilation opening 221) communicates with the outside of the cartridge 200. The ventilation valve chamber 214 may communicate with outside air via the ventilation opening 221. A valve 222 and a coil spring 223 are disposed in the ventilation valve chamber 214. The valve 222 is movable in the front-rear direction 8 between a closing position and an open position. When the valve 222 is located at the closing position, the valve 222 closes the ventilation opening 221. When the valve 222 is located at the open position, the valve 222 opens the ventilation opening 221. The coil spring 223 urges the valve 222 in a direction in which the coil spring 223 moves the valve 222 from the open position to the closing position, i.e., toward the rear.

During attachment of the cartridge 200 to the installation case 150, the rod 153 enters the ventilation valve chamber 214 via the ventilation opening 221 of the cartridge 200. The rod 153 entering the ventilation valve chamber 214 moves the valve 222 toward the front from the closing position against the urging force of the coil spring 223. The movement of the valve 222 to the open position allows the upper liquid chamber 211 to communicate with outside air. The

configuration for opening the ventilation opening 221 is not limited to the specific example. In other embodiments, for example, the ventilation opening 221 may be closed by a film, and the rod 153 may penetrate the film of the ventilation opening 221.

The supply tube 230 protrudes rearward from the rear wall 202 at a lower portion of the housing 201. The supply tube 230 has an opening at its protruding end (i.e., a rear end). That is, the air valve chamber 213 enables the liquid chamber 210 communicating therewith via the through hole 219 to communicate with the outside of the cartridge 200. The air valve chamber 213 is an example of a channel whose one end (e.g., the through hole 219) communicates with the liquid chamber 210 (more specifically, the lower liquid chamber 212) and whose other end (e.g., the ink supply port 234) communicates with the outside of the printer 200. A sealer 231, a valve 232, and a coil spring 233 are disposed in the ink valve chamber 213.

The sealer 231 has the ink supply port 234 in the center thereof. The ink supply port 234 penetrates the sealer 231 in the front-rear direction 8. The ink supply port 234 has an inside diameter slightly smaller than an outside diameter of the needle 81. The valve 232 is movable in the front-rear direction 8 between a closing position and an open position. When the valve 232 is located at the closing position, the valve 232 contacts the sealer 231 to close the ink supply port 234. When the valve 232 is located at the open position, the valve 232 is spaced from the sealer 231 to open the ink supply port 234. The coil spring 233 urges the valve 232 in a direction in which the coil spring 223 moves the valve 222 from the open position to the closing position, i.e., toward the rear. The coil spring 233 has a greater urging force than the coil spring 186.

During attachment of the cartridge 200 to the installation case 150, the supply tube 230 enters the inside of the guide 182 and then the needle 181 enters the ink valve chamber 213 via the ink support port 234. At that time, the needle 181 fluid-tightly contacts an inner circumferential surface of the ink supply port 234 while elastically deforming the sealer 231. As the cartridge 200 is further moved into the installation case 150, the needle 181 moves the valve 232 toward the front against the urging force of the coil spring 233. In response, the valve 232 moves the valve 185, which protrudes from the opening 183 of the needle 181, toward the rear against the urging force of the coil spring 186.

Thus, as illustrated in FIG. 5, the ink supply port 234 and the opening 183 are opened, thereby providing communication between the ink valve chamber 213 of the supply tube 230 and the internal space of the needle 181. That is, in a state where the cartridge 200 is fully attached to the installation case 150, the ink valve chamber 213 and the internal space of the needle 181 constitute a channel that may provide communication between the liquid chamber 210 of the cartridge 200 and the liquid chamber 171 of the tank 160.

Further, in such a state, the liquid chamber 210 and the liquid chamber 171 partially overlap each other as viewed in the horizontal direction. This configuration may therefore enable the ink stored in the liquid chamber 210 to move to the liquid chamber 171 of the tank 160 via the supply tube 230 and the joint 180, which connected to each other, due to a hydraulic pressure difference therebetween.

As illustrated in FIGS. 4A and 4B, the upper wall 204 of the cartridge 200 includes a protrusion 241. The protrusion 241 protrudes upward from an exterior surface of the upper wall 204 and is elongated in the front-rear direction 8. The protrusion 241 includes a lock surface 242 and an inclined surface 243. The lock surface 242 and the inclined surface

243 are located above the upper wall 204. The lock surface 242 faces toward the front in the front-rear direction 8 and extends in both the up-down direction 7 and the right-left direction 9. The inclined surface 243 is angled relative to the upper wall 204 and faces upwardly rearward.

In a state where the cartridge 200 is fully attached to the installation case 150, the lock surface 242 contacts the lock pin 156. During attachment of the cartridge 200 to the installation case 150, the inclined surface 243 guides the lock pin 156 to a position where the lock pin 156 contacts the lock surface 242. In a state where the lock surface 242 and the lock pin 156 contact with each other, the cartridge 200 is retained at the particular position (refer to FIG. 5) against the urging force of each of the coil springs 186, 223, and 233.

The cartridge 200 further includes a plate-shaped member that is disposed further to the front than the lock surface 42. The plate-shaped member extends upward from the upper wall 204. The plate-shaped member has an upper surface that may be an operable portion 244 to be used by a user for detaching the cartridge 200 from the installation case 150. In a state where the cartridge 200 is fully attached to the installation case 150 and the cover 87 is located at the uncovering position, the operable portion 244 may be accessed by the user. As the operable portion 244 is pressed downward, the cartridge 200 rotates and the lock surface 242 moves to below the lock pin 156. Thus, the cartridge 200 is allowed to be detached from the installation case 150.

The cartridge 200 further includes the light blocking rib 245 at the exterior surface of the upper wall 204. The light blocking rib 245 is disposed further to the rear than the protrusion 241. The light blocking rib 245 protrudes upward from the exterior surface of the upper wall 204 and is elongated in the front-rear direction 8. The light blocking rib 245 may be made of material that may block light outputted by the light emitter of the installation sensor 154 or have a color that may block the light. In a state where the cartridge 200 is fully attached to the installation case 150, the light blocking rib 245 is located on a path in which light emitted from the light emitter travels to the light receiver. That is, the installation sensor 154 is configured to, in response to a detection that a corresponding cartridge 200 is fully attached to the installation case 150, output a low level signal to the controller 130. On the other hand, the installation sensor 154 is configured to, in response to a detection that a corresponding cartridge 200 is not fully attached to the installation case 150, output a high level signal to the controller 130. That is, the controller 130 determines, based on a type of a signal outputted by the installation sensor 154, whether a corresponding cartridge 200 is fully attached to the installation case 150.

The cartridge 200 further includes an IC board 247 at the exterior surface of the upper wall 204. The IC board 247 is disposed between the light blocking rib 245 and the protrusion 241 in the front-rear direction 8. The IC board 247 includes the plurality of electrodes 248. The IC board 247 further includes a memory. The electrodes 248 are electrically connected to the memory of the IC board 247. The electrodes 248 are exposed at an upper surface of the IC board 247 and are configured to be electrically connected to the contact 152 in a state where the cartridge 200 is fully attached to the installation case 150. The controller 130 is configured to read and write various information from and into the memory of the IC board 247 via the contact 152 and the electrodes 248. The IC board 247 is an example of a cartridge memory. Each of the contacts 152 is an example of an interface.

The memory of the IC board 247 stores various information such as an ink amount V_c , individual identifying information identifying the cartridge 200, and type information indicating the cartridge 200. For a completely new cartridge 200, a memory of its IC board 247 stores an initial ink amount V_{c0} as the ink amount V_c . The initial ink amount V_{c0} indicates an amount of ink stored in a completely new cartridge 200. Each of various information stored in the memory of the IC board 247 is an example of cartridge information. The completely new cartridge 200 refers to a cartridge 200 that has not been used yet before and that has not yet allowed ink to flow out from the cartridge 200 after manufactured and sold.

The memory of the IC board 247 has, for example, an unrewritable area in which information is not rewritable by the controller 130 and a rewritable area in which information is rewritable by the controller 130. For example, the identifying information and the type information are stored in the unrewritable area, and the ink amount V_c is stored in the rewritable area.

Controller 130

As illustrated in FIG. 6, the controller 130 includes a CPU 131, a ROM 132, a RAM 133, an EEPROM 134, and an ASIC 135. The ROM 132 stores a program used by the CPU 131 for controlling various operations. The RAM 133 is used as a storage area for temporarily storing data and/or signals to be used by the CPU 131 during execution of the program, and also as a working area for processing data. The EEPROM 134 stores setting information that needs to be retained after power of the printer 10 is turned off. The ROM 132, the RAM 133, and the EEPROM 134 are an example of a memory.

The ASIC 135 is used for activating the feed roller 23, the conveying rollers 25, the output rollers 27, and the head 21. The controller 130 is configured to control the ASIC 135 to drive a motor to rotate the feed roller 23, the conveying rollers 25, and the output rollers 27. The controller 130 is further configured to control the ASIC 135 to output a drive signal to a drive element of the head 21 to eject ink through the head 21 via one or more of the nozzles 29. The ASIC 135 is configured to output various drive signals in accordance with an amount of ink to be ejected via each of the nozzles 29.

The printer 10 further includes a display 17 and an operation panel 22, each of which is connected to the ASIC 135. The display 17 may be, for example, a liquid crystal display or an organic electroluminescent display. The display 17 includes a screen for displaying various information. The display 17 is an example of a notification device. Nevertheless, the notification device is not limited to the display 17. In other embodiments, for example, the notification device may be a speaker, an LED lamp, or a combination of the speaker and the LED lamp. The operation panel 22 is configured to output an operation signal to the controller 130 in response to a user operation. The operation panel 22 may include, for example, a physical button and/or a touchscreen on the display 17.

The contacts 152, the cover sensor 88, the installation sensors 154, the liquid level sensors 155, and the temperature sensor 89 are also each connected to the ASIC 135 electrically. The controller 130 is configured to access the memory of the IC board 247 of the cartridge 200 fully attached to the installation case 150. The controller 130 is configured to detect the position of the cover 87 via the cover sensor 88. The controller 130 is further configured to determine, via the installation sensor 154, whether a corresponding cartridge 200 is fully attached or not to the

installation case 150. The controller 130 is further configured to determine whether the surface level of ink stored in the liquid chamber 171 is higher than or equal to the predetermined level P. The controller 130 is further configured to detect the temperature in the installation case 150 indirectly via the temperature sensor 89.

The ROM 132 stores a predetermined ink amount Vsc and a predetermined ink amount Vcc. The predetermined ink amount Vsc refers to an amount of ink stored in the liquid chamber 171 of the tank 160 when a corresponding liquid level sensor 155 outputs a high level signal. The predetermined ink amount Vcc refers to an amount of ink stored in the liquid chamber 210 of the cartridge 200 when the corresponding liquid level sensor 155 outputs a high level signal. In the illustrative embodiment, the predetermined ink amount Vcc may be zero.

The ROM 132 stores a plurality of specified times ST for each of the types of the cartridges 200.

The ROM 132 further stores temperature correction information. The temperature correction information may indicate a correspondence between temperature t in the installation case 150 detected by the temperature sensor 89 and a correction degree Δ of each specified time ST. For example, the temperature correction information may be expressed by an equation of the form $\Delta = p*t + q$ ("p" and "q" are constants). In other embodiments, for example, the temperature correction information may be a table indicating the correspondence between the temperature t and the correction degree Δ .

The EEPROM 134 stores various information in association with the respective four cartridges 200 to be attached to the installation case 150, i.e., in association with the respective tanks 160 with which the respective cartridges 200 communicate. The various information includes, for example, the ink amount Vc, the ink amount Vs, a function F1, a function F2, a C_Empty flag, an S_Empty flag, a count value SN, a count value TN, a threshold N_{th} , and an initial setting flag.

The ink amount Vc, the identifying information, and the type information may be read by the controller 130 from the memory of the IC board 247 via the contact 152 in a state where the cartridge 200 is fully attached to the installation case 150. Nevertheless, in other embodiments, for example, the function F1 and the function F2 may be stored in the ROM 132 instead of the EEPROM 134.

The ink amount Vc indicates an amount of ink stored in the liquid chamber 210 of the cartridge 200. The ink amount Vs indicates an amount of ink stored in the liquid chamber 171 of the tank 160. The ink amount Vs is calculated using appropriate one of the function F1 and the function F2. The ink amount Vc is calculated using the ink amount Vs calculated using appropriate one of the function F1 and the function F2, and a total ink amount Vt.

The function F1 and the function F2 may be information that indicates a correspondence among the total ink amount Vt and the ink amount Vs. Ink stored in the liquid chamber 210 of the cartridge 200 and ink stored in the liquid chamber 171 of the tank 160 are in equilibrium while the surface of ink stored in the liquid chamber 210 and the surface of ink stored in the liquid chamber 171 are at the same level in the top-bottom direction 7. That is, when equilibrium is reached, ink stops moving between the liquid chamber 210 of the cartridge 200 and the liquid chamber 171 of the tank 160. A relationship between the total ink amount Vt and the ink amount Vs in equilibrium may be expressed by an approximation in which an actual measured value is approximated by a function.

For example, the relationship of the ink amount Vs relative to the total ink amount Vt may be expressed approximately using the functions F1 and F2. The function F1 indicates the relationship of the ink amount Vs relative to the total ink amount Vt when the total ink amount Vt is greater than or equal to a threshold Vh. For example, the function F1 may be expressed by an equation of the form $Vs = a*Vt + b$ ("a" and "b" are constants). The function F2 indicates the relationship of the ink amount Vs relative to the total ink amount Vt when the total ink amount Vt is lower than the threshold Vh. For example, the function F2 may be expressed by an equation of the form $Vs = c*Vt + d$ ("c" and "d" are constants).

The threshold Vh indicates a value that corresponds to the total ink amount Vt when the surface of ink stored in the liquid chamber 210 of the cartridge 200 contacts the upper surface 215U or the lower surface 215L of the partition wall 215. Therefore, when the surface level of ink stored in the liquid chamber 210 of the cartridge 200 is higher than the partition wall 215, i.e., when the total ink amount Vt is greater than or equal to the threshold Vh, the ink amount Vs is calculated using the function F1. When the surface level of ink stored in the liquid chamber 210 of the cartridge 200 contacts the partition wall 215 or lower than the partition wall 215, i.e., when the total ink amount Vt is less than the threshold Vh, the ink amount Vs is calculated using the function F2. The ink amount Vc is calculated by subtraction of the ink amount Vs from the total ink amount Vt.

The count value SN indicates a value corresponding to an ink discharge amount Dh (i.e., an ink amount indicated by a drive signal) which is instructed to the head 21 to discharge after a signal outputted by the liquid level sensor 155 has changed from the low level signal to the high level signal. The count value SN is updated to increase and approach to a threshold N_{th} . In this case, an initial value of the count value SN may be 0 (zero). The threshold N_{th} corresponds to a volume of a portion of the liquid chamber 171 between the upper edge of the outlet 174 and the predetermined level P. Nevertheless, in other embodiments, for example, the count value SN may be updated to decrease and approach to a threshold N_{th} . In such a case, an initial value of the count value SN may be a value corresponding to the volume, and the threshold N_{th} may be 0 (zero).

The count value TN indicates a value corresponding to an ink discharge amount Dh (i.e., an ink amount indicated by a drive signal) which is instructed to the head 21 to discharge after a signal outputted by the installation sensor 154 has changed from the high level signal to the low level signal. The count value TN increases and its initial value may be "0 (zero)". Nevertheless, in other embodiments, for example, the count value TN may decrease. In such a case, the initial value of the count value TN may be a value corresponding to the total ink amount Vt.

The C_Empty flag indicates information as to whether the cartridge 200 is in a cartridge empty state. The C_Empty flag is assigned with one of values "ON" and "OFF". The value "ON" indicates that the cartridge 200 is in the cartridge empty state. The value "OFF" indicates that the cartridge 200 is not in the cartridge empty state.

The cartridge empty state refers to a state where the cartridge 200 (more specifically, the liquid chamber 210) is substantially empty of ink. In other words, the cartridge empty state refers to a state where ink does not move from the liquid chamber 210 to the liquid chamber 171 communicating with each other. In still other words, the cartridge empty state refers to a state where the surface level of ink

stored in the tank **160** communicating with the cartridge **200** is lower than the predetermined level **P**.

The **S_Empty** flag indicates information as to whether the tank **160** is in an ink empty state. The **S_Empty** flag is assigned with one of values “ON” and “OFF”. The value “ON” indicates that the tank **160** is in the ink empty state. The value “OFF” indicates that the tank **160** is not in the ink empty state. The ink empty state refers to a state where the surface level of ink stored in the tank **160** (more specifically, the liquid chamber **171**) has reached proximity to the upper edge of the outlet **174**. In other words, the ink empty state refers to a state where the count value **SN** is greater than or equal to the threshold **N_{th}**. If ink ejection is performed by the head **21** repeatedly even after the tank **160** has become in the ink empty state, the surface level of ink stored in the tank **160** may become lower than the upper edge of the outlet **174**. This may cause intrusion of air into the ink channel that extends from the tank **160** to the head **21** or intrusion of air into the head **21** (i.e., air-in). Such an air-in may further cause insufficient supply of ink to each of the nozzles **29**, thereby causing an ink ejection failure.

Operation of Printer **10**

Referring to FIGS. 7 to 9C, an operation performed by the printer **10** according to the embodiment will be described. Each processing illustrated in FIGS. 7 and 8 may be executed by the CPU **131** of the controller **130**. Each processing described below may be executed by the CPU **131** that reads the program stored in the ROM **132** or may be executed by a hardware circuit installed on the controller **130**. An order in which processing steps are executed in each processing may be changed without departing from the spirit and scope of the invention.

Image Recording Processing

The controller **130** is configured to, in response to input of a recording instruction to the printer **10**, execute image recording processing (refer to FIG. 7). The recording instruction is an example of a discharge instruction for causing the printer **10** to execute recording processing for recording an image represented by an image data onto a sheet. In one example, the printer **10** may receive a user operation for providing a recording instruction, via the operation panel **22**. In another example, the printer **10** may receive a recording instruction via its communication interface from an external device.

The controller **130** determines, with respect to each of the four **S_Empty** flags of the cartridges **200**, which value is assigned (e.g., step **S11**). If the controller **130** determines that at least one of the **S_Empty** flags of the cartridges **200** is assigned with the value “ON” (e.g., “ON” in step **S11**), the controller **130** displays an **S_Empty** notification screen on the display **17** (e.g., step **S12**). The **S_Empty** notification screen provides notification to the user that a tank **160** corresponding to the **S_Empty** flag that is assigned with the value “ON” is in the ink empty state and thus ink discharge via the head **21** cannot be performed. The **S_Empty** notification screen may include information indicating, for example, color of ink stored in the tank **160** having the ink empty state, and/or the ink amounts **Vc** and **Vs**. In other embodiments, for example, if the controller **130** determines that at least one of the **S_Empty** flags of the cartridges **200** is assigned with the value “ON” (e.g., “ON” in step **S11**), in step **S12**, the controller **130** may display a **C_Empty** notification screen in addition to the **S_Empty** notification screen. Displaying the **S_Empty** notification screen on the display **17** in step **S12** is an example of causing the notification device to provide a first alert.

FIG. 9A illustrates an example of the **S_Empty** notification screen. The **S_Empty** notification screen may include objects **251**, **252**, and **253**. The object **251** may be a message prompting replacement of one or more cartridges **200**, for example, a text string “PLEASE REPLACE INK CARTRIDGE.” The object **252** may indicate a type of the one or more cartridges **200** that need to be replaced, for example, a letter “M” indicating a magenta cartridge **200**. The object **253** may illustrate the one or more empty cartridges **200**.

10 The controller **130** executes processing in steps **S13** to **S22** on each of the one or more cartridges **200** whose **S_Empty** flags are assigned with the value “ON” (hereinafter, also referred to as an “ON” cartridge **200**). That is, processing in each of steps **S13** to **S22** are executed on each of the one or more “ON” cartridges **200**, among the four cartridges **200**. The same processing is executed on all of the one or more “ON” cartridges **200** in steps **S13** to **S22**, and therefore, a description will be provided on processing in steps **S13** to **S22** to be executed on one of the one or more “ON” cartridges **200**.

15 Subsequent to step **S12**, the controller **130** receives a signal outputted by the installation sensor **154** (e.g., step **S13**). Subsequent to step **S13**, the controller **130** determines whether the signal received from the installation sensor **154** has changed from the high level signal (H) to the low level signal (L) (e.g., step **S14**). The controller **130** repeats steps **S13** and **S14** at predetermined intervals until the controller **130** determines that the signal outputted by the installation sensor **154** has changed from the low level signal (L) to the high level signal (H) and then has further changed from the high level signal (H) to the low level signal (L) again (e.g., NO in step **S14**). In other words, the controller **130** repeats steps **S13** and **S14** while the currently used cartridge **200** is detached from the installation case **150** and until a new cartridge **200** is fully attached to the installation case **150** as its replacement.

20 If, in step **S14**, the controller **130** determines that the controller **130** has received the low level signal, the high level signal, and the low level signal again in this order from the installation sensor **154** (e.g., YES in step **S14**), in step **S15**, the controller **130** reads the identifying information, the type information, and the ink amount **Vc** from the IC board **247** of the currently-attached cartridge **200** via the contact **152** and stores the read information in the EEPROM **134**. At 25 that time, the controller **130** overwrites the ink amount **Vc** currently stored in the EEPROM **134** with the newly obtained ink amount **Vc** (e.g., the ink amount **Vc** read from the IC board **247**).

25 Subsequent to step **S15**, the controller **130** closes the **S_Empty** notification screen and displays an ink refilling notification screen on the display **17** (e.g., step **S16**). The ink refilling notification screen provides notification to the user that ink is flowing into a corresponding tank **160** from the cartridge **200**. Displaying the ink refilling notification screen on the display **17** is an example of causing the notification device to provide a third alert.

30 FIG. 9B illustrates an example of the ink refilling notification screen. The ink refilling notification screen may include objects **254** and **255**. The object **254** may be a message informing the user that ink is flowing into a corresponding tank **160** from the cartridge **200**, for example, a text string “TANK (2) IS BEING REFILLED WITH INK OF CARTRIDGE (1)”. The object **255** may illustrate a newly-attached cartridge **200** and a corresponding tank **160** in the printer **10**.

35 Subsequent to step **S16**, the controller **130** determines whether the signal received from the liquid level sensor **155**

has changed from the high level signal (H) to the low level signal (L) (e.g., step S17). In response attachment of the completely new cartridge 200 to the installation case 150, ink flows from the liquid chamber 210 of the newly-attached cartridge 200 to the liquid chamber 171 of the corresponding tank 160. In response to the surface level of ink stored in the liquid chamber 171 having reached the predetermined level P, the signal outputted by the liquid level sensor 155 changes from the high level signal to the low level signal. If the controller 130 determines that the signal received from the liquid level sensor 155 has not changed from the high level signal to the low level signal (e.g., NO in step S17), the controller 130 executes processing for determining an elapsed time T (e.g., step S18).

The controller 130 reads an appropriate specified time ST from the ROM 132 based on the type information read from the IC board 247 of the newly-attached cartridge 200 in step S15, and stores the read specified time ST in the RAM 133. Then, the controller 130 corrects the specified time ST stored in the RAM 133, based on the temperature t indicated by a signal received from the temperature sensor 89 and the temperature correction information stored in the ROM 132. More specifically, for example, the controller 130 calculates a correction amount A based on the temperature correction information (e.g., $\Delta=p*t+q$ ("p" and "q" are constants)), and then obtains a corrected specified time ST by adding the correction amount A to the original specified time ST read from the ROM 132.

Thereafter, the controller 130 determines an elapsed time T that may be an amount of time that passes from occurrence of the event that the controller 130 determines that the controller 130 has received the low level signal, the high level signal, and the low level signal in this order from the installation sensor 154 (e.g., YES in step S14) until the current time. In one example, the controller 130 may store, in the RAM 133, the time at which the controller 130 receives the low level signal after receiving the high level signal from the installation sensor 154. The controller 130 may then determine the elapsed time T based on the time stored in the RAM 133 and the current time. In another example, the controller 130 may start a timer when the controller 130 receives the low level signal after receiving the high level signal from the installation sensor 154, and determine the elapsed time T based on the time indicated by the timer.

The controller 130 determines whether the elapsed time T has exceeded the corrected specified time ST (e.g., step S18). If the controller 130 determines that the elapsed time T has not exceeded the corrected specified time ST (e.g., NO in step S18), the controller 130 repeats steps S17 and S18 until the controller 130 receives the low level signal or until the controller 130 determines that the elapsed time T has exceeded the corrected specified time ST. That is, the controller 130 waits until the surface level of ink stored in the liquid chamber 171 rises to the predetermined level P or until the elapsed time T has exceeded the corrected specified time ST since the cartridge 200 is attached to the installation case 150.

If the controller 130 determines that the elapsed time T has exceeded the corrected specified time ST (e.g., YES in step S18), the controller 130 closes the ink refilling notification screen and displays the S_Empty notification screen on the display 17 (e.g., step S19). The S_Empty flag screen displayed in step S19 may be the same as or different from the S_Empty flag screen displayed in step S12. Subsequent to step S19 the controller 130 executes step S11 and the subsequent steps again. Displaying the S_Empty notification

screen on the display 17 in step S19 is an example of causing the notification device to provide a fourth alert.

If the controller 130 determines that the signal received from the liquid level sensor 155 has changed from the high level signal (H) to the low level signal (L) (e.g., YES in step S17), the controller 130 calculates the total ink amount Vt of the post-cartridge replacement. More specifically, the controller 130 calculates the ink amount Vs of the pre-cartridge replacement based on the count value SN of the pre-cartridge replacement stored in the EEPROM 134 and the ink amount Vsc stored in the ROM 132 ($Vs=Vsc-SN$), and stores the calculated ink amount Vs in the EEPROM 134. The ink amount Vs of the pre-cartridge replacement is equal to the total ink amount Vt of the pre-cartridge replacement. Thereafter, the controller 130 calculates the total ink amount Vt of the post-cartridge replacement based on the calculated ink amount Vs and the ink amount Vc read from the memory of the IC board 247 of the replacement cartridge 200 ($Vt=Vs+Vc$). With the cartridge replacement, the ink amount Vc that indicates the amount of ink stored in the liquid chamber 210 of the newly attached cartridge 200 is added to the ink amount Vs ($=Vsc-SN$) that indicates the amount of ink stored in the liquid chamber 171 of the corresponding tank 160 immediately before the replacement cartridge 200 is attached.

Subsequent to step S17, the controller 130 calculates, based on the calculated total ink amount Vt and an appropriate one of the functions F1 and F2 read from the EEPROM 134, the ink amount Vc and the ink amount Vs after ink movement from the liquid chamber 210 to the liquid chamber 171 is completed (e.g., step S20). In response to cartridge replacement, ink stored in the liquid chamber 210 of the newly-attached cartridge 200 flows into the liquid chamber 171 of the corresponding tank 160 via the needle 181. Thus, the ink amount Vc of ink stored in the liquid chamber 210 decreases and the ink amount Vt of ink stored in the liquid chamber 171 increases. Consequently, ink stored in the liquid chamber 210 of the cartridge 200 and ink stored in the liquid chamber 171 of the tank 160 become in equilibrium while the surface of ink stored in the liquid chamber 210 and the surface of ink stored in the liquid chamber 171 are at the same level in the top-bottom direction 7.

The controller 130 determines whether the obtained total ink amount Vt is greater than or equal to the threshold Vh. For example, in a case where a completely new cartridge 200 is attached to the installation case 150, the calculated total ink amount Vt is greater than or equal to the threshold Vh. If the controller 130 determines that the calculated total ink amount Vt is greater than or equal to the threshold Vh, the controller 130 calculates the ink amount Vs based on the total ink amount Vt using the function F1. The controller 130 then stores the calculated ink amount Vc in the EEPROM 134 (e.g., step S21). At that time, the controller 130 overwrites the ink amount Vs currently stored in the EEPROM 134 with the newly calculated ink amount Vs. The controller 130 also stores the calculated ink amount Vc in the memory of the IC board 247 via the contact 152 (e.g., step S21). At that time, the controller 130 overwrites the ink amount Vc currently stored in the IC board 247 with the newly calculated ink amount Vc.

Subsequent to step S21, the controller 130 clears the ink empty state and the cartridge empty state (e.g., step S22).

More specifically, for example, the controller 130 assigns the value "OFF" to each of the S_Empty flag and the C_Empty flag. Further, the controller 130 clears an alert by closing the one or more currently displayed screens, e.g.,

one or both of the S_Empty notification screen and the C_Empty notification screen. The controller 130 displays the calculated ink amounts Vc and Vs on the display 17. The controller 130 may also display the calculated total ink amount Vt on the display 17. The total ink amount Vt and the ink amounts Vc and Vs may be indicated by numeric values or by images such as a bar indicator. Both of the ink amount Vc and the ink amount Vs are not necessarily indicated. In one example, one of the ink amount Vc and the ink amount Vs, for example, only the ink amount Vc may be indicated. Subsequent to step S22, the controller 130 executes step S11 and the subsequent steps again.

If the controller 130 determines that none of the S_Empty flags is assigned with the value “ON”, i.e., if the controller 130 determines that all of the S_Empty flags are assigned with the value “OFF” (e.g., OFF in step S11), the controller 130 obtains a signal currently outputted by each of the four liquid level sensors 155 (e.g., step S23). In step S23, the controller 130 stores, in the RAM 133, information indicating one of the high level signal and the low level signal received from each of the liquid level sensors 155.

Subsequent to step S23, the controller 130 executes recording of one of one or more images represented by image data included in the recording instruction, onto a single sheet (e.g., step S24). More specifically, for example, the controller 130 controls the feed roller 23 and the conveying rollers 25 to convey one of one or more sheets supported by the feed tray 15. The controller 130 also controls the head 21 to eject ink therefrom and controls the output rollers 27 to output the sheet on which the image has been recorded, onto the output tray 16. That is, in a case where all of the four S_Empty flags are assigned with the value “OFF” (e.g., OFF in step S11), the controller 130 executes step S24. That is, the controller 130 allows the head 21 to discharge ink. In a case where at least one of the four S_Empty flags is assigned with the value “ON” (e.g., ON in step S11), the controller 130 does not execute step S24. That is, the controller 130 prohibits ink discharge through the head 21.

In response to completing image recording onto a single sheet in accordance with the recording instruction, the controller 130 obtains a signal currently outputted by each of the four liquid level sensors 155 (e.g., step S25). Similar to step S23, the controller 130 stores, in the RAM 133, information indicating one of the high level signal and the low level signal received from each of the installation sensors 155 (e.g., step S25). Subsequent to step S25, the controller 130 executes count processing (e.g., step S26). The count processing may be for updating the count values TN and SN, and the values of the C_Empty flag and the S_Empty flag based on the signals received from each of the liquid level sensors 155 in steps S23 and S25. Details of the count processing will be described later with reference to FIG. 8.

Subsequent to step S26, the controller 130 repeats steps S11 to S27 until all of the one or more images represented by the image data included in the recording instruction have been recorded on respective sheets, i.e., until no more image is left for another page (e.g., YES in step S27). In response to completing recording of all of the one or more images represented by the image data included in the recording instruction onto the respective sheets (e.g., NO in step S27), the controller 130 may determine, with respect to each of the four S_Empty flags and/or each of the four C_Empty flags, which value is assigned (e.g., steps S28 and S29).

More specifically, for example, if the controller 130 determines that at least one of the S_Empty flags is assigned

with the value “ON” (e.g., ON in step S28), the controller 130 displays the S_Empty notification screen on the display 17 (e.g., step S30). Step S30 is another example of causing the notification device to provide the first alert.

If the controller 130 determines that all of the S_Empty flags are assigned with the value “OFF” and at least one of the C_Empty flags is assigned with the value “ON” (e.g., OFF in step S28 and ON in step S29), the controller 130 displays the C_Empty notification screen on the display 17 (e.g., step S31).

The S_Empty flag screen displayed in step S30 may be the same as the S_Empty flag screen displayed in step S12. The C_Empty notification screen provides notification to the user that the cartridge 200 corresponding to the C_Empty flag assigned with the value “ON” is in the cartridge empty state. The C_Empty notification screen may include information indicating, for example, color of ink stored in the cartridge 200 having the cartridge empty state, and/or the ink amounts Vc and Vs.

FIG. 9C illustrates an example of the C_Empty notification screen. Similar to the S_Empty notification screen (refer to FIG. 9A), the C_Empty notification screen may include the objects 251, 252, and 253. The C_Empty notification screen may further include an object 256. The object 256 may be a message informing the user that printing is available without cartridge replacement, for example, a text string “PRINTING IS AVAILABLE USING INK REMAINING IN TANK.”

If the controller 130 determines that all of the S_Empty flags are assigned with the value “OFF” and also determines that all of the C_Empty flags are assigned with the value “OFF” (e.g., OFF in step S29), the controller 130 ends the image recording processing.

Nevertheless, the discharge instruction is not limited to the recording instruction. In other embodiments, for example, the discharge instruction may be a maintenance instruction for instructing maintenance of the nozzles 29 (e.g., purging). The controller 130 is further configured to, in response to receiving a maintenance instruction via the operation panel 22, execute similar processing described in FIG. 7. Nevertheless, in such a case, the following are different points from the case where the recording instruction has been received. In step S24, the controller 130 controls a maintenance mechanism to perform ink discharge via the nozzles 29. Subsequent to the count processing, the controller 130 skips step S27 and executes step S28 and the subsequent steps.

Count Processing

Hereinafter, referring to FIG. 8, the count processing executed by the controller 130 in step S26 will be described. The controller 130 executes the count processing on the four cartridges 200 individually. Nevertheless, the same processing is executed on all of the cartridges 200, and therefore, a description will be provided with respect to the count processing to be executed on one of the cartridges 200.

The controller 130 compares the information indicating the signal received from the liquid level sensor 155 stored in the RAM 133 in step S23 with the information indicating the signal received from the liquid level sensor 155 stored in the RAM 133 in step S25 (e.g., step S41). That is, the controller 130 determines, with respect to the signal outputted by each of the liquid level sensors 155, whether the type of signal is different between before and after step S24 which was executed immediately before the count processing (e.g., step S26).

If the controller 130 determines that both of the information indicating the signal received from the liquid level

sensor 155 stored in the RAM 133 in step S23 and the information indicating the signal received from the liquid level sensor 155 stored in the RAM 133 in step S25 indicate the low level signal (L) (i.e., if the controller 130 determines that the type of the signal outputted by the liquid level sensor 155 is the same between before and after step S24) (e.g., L to L in step S41), the controller 130 updates the count value TN (e.g., step S42). That is, the controller 130 adds, to the count value TN, a value corresponding to the ink amount for discharge instructed immediately before step S24.

Subsequent to step S42, the controller 130 calculates the current total ink amount Vt (e.g., step S43). More specifically, for example, the controller 130 calculates the total ink amount Vt of the post-cartridge replacement that is a sum of the ink amounts Vc and Vs stored in the EEPROM 134 after cartridge replacement. Then, the controller 130 calculates the current total ink amount Vt by subtracting the ink amount corresponding to the count value TN from the calculated total value Vt ($Vt=Vt-TN$). The controller 130 calculates, based on the calculated current total ink amount Vt and an appropriate one of the functions F1 and F2, the ink amount Vc and the ink amount Vs (e.g., step S43).

The controller 130 determines whether the calculated current total ink amount Vt is greater than or equal to the threshold Vh. If the controller 130 determines that the calculated current total ink amount Vt is greater than or equal to the threshold Vh, the controller 130 calculates the ink amount Vs based on the current total ink amount Vt using the function F1. If the controller 130 determines that the calculated current total ink amount Vt is less than the threshold Vh, the controller 130 calculates the ink amount Vs based on the current total ink amount Vt using the function F2. The controller 130 then calculates the ink amount Vc by subtracting the calculated ink amount Vs from the current total ink amount Vt.

Subsequent to step S43, the controller 130 displays the calculated total ink amount Vt or both of the calculated ink amounts Vc and Vs on the display 17 (e.g., step S44). Subsequent to step S44, the controller 130 overwrites the ink amount Vc currently stored in the IC board 247 of the cartridge 200 with the newly calculated ink amount Vc (e.g., step S45).

If the controller 130 determines that the information stored in the RAM 133 in step S23 indicates the low level signal (L) and the information stored in the RAM 133 in step S25 indicates the high level signal (H) (i.e., if the controller 130 determines that the type of the signal outputted by the liquid level sensor 155 is different between before and after step S24) (e.g., L to H in step S41), the controller 130 assigns the value "ON" to the C_Empty flag (e.g., step S46). Such change of the signal outputted by the liquid level sensor 155 occurs when the surface level of ink stored in the liquid level 171 reaches the predetermined level P during execution of step S24. From then on, ink does not move between the cartridge 200 and the tank 160.

Subsequent to step S46, the controller 130 reads the predetermined ink amount Vcc (=0) from the ROM 132 and assigns the predetermined ink amount Vcc to the ink amount Vc (e.g., step S47). Similarly, the controller 130 reads the predetermined ink amount Vsc from the ROM 132 and assigns the predetermined ink amount Vsc to the ink amount Vc (e.g., step S47). Here, the predetermined ink amount Vsc corresponds to the volume of a portion of the liquid chamber 171 between the upper edge of the outlet 174 and the surface of ink lower than the predetermined level P. The ink amounts Vc and Vs calculated in the count processing may include errors. Therefore, the controller 130 resets the accumulated

errors by assigning the predetermined ink amount Vcc and the predetermined ink amount Vsc to the ink amount Vc and the ink amount Vs, respectively, at the timing at which the signal outputted by the liquid level sensor 155 changes from the low level signal to the high level signal. Subsequent to step S46, the controller 130 calculates the current total ink amount Vt as the same value as the ink amount Vs ($Vt=Vsc$) (e.g., step S47). When the ink amount Vc becomes 0 (zero), the total ink amount Vt is equal to the ink amount Vs.

Subsequent to this, the controller 130 displays the current total ink amount Vt or both of the current ink amounts Vc and Vs on the display 17 (e.g., step S48). Subsequent to step S48, the controller 130 overwrites the ink amount Vc currently stored in the IC board 247 of the cartridge 200 with the newly calculated ink amount Vc (=0) (e.g., step S49).

The signal outputted by the liquid level sensor 155 may change during execution of step S24. Therefore, the predetermined ink amount Vsc read in step S47 indicates the ink amount immediately prior to the change of the signal outputted by the liquid level sensor 155 but not the ink amount stored in the tank 160 at the moment when the signal outputted by the liquid level sensor 155 changes. Nevertheless, there is only a slight difference in those ink amounts. Therefore, the predetermined ink amount Vsc read in step S47 may be approximately equal to the ink amount Vs at the moment when the signal outputted by the liquid level sensor 155 changes.

Subsequent to step S49, the controller 130 updates the count value SN stored in the EEPROM 134, using a value corresponding to the ink amount for discharge instructed immediately before step S24 (e.g., step S50). In other words, if the controller 130 determines that the signal received from the liquid level sensor 155 has changed from the low level signal (L) to the high level signal (H), the controller 130 adds, to the count value SN stored in the EEPROM 134, the value corresponding to the ink amount for discharge instructed immediately before step S24. Further, the controller 130 adds, to the count value TN stored in the EEPROM 134, the value corresponding to the ink amount for discharge instructed immediately before step S24 (e.g., step S40).

Subsequent to step S50, the controller 130 calculates the ink amount Vs (e.g., step S51). The ink amount Vs obtained in step S51 may be calculated by a subtraction of the ink amount corresponding to the count value SN stored in the EEPROM 134 from the predetermined ink amount Vsc stored in the ROM 132. As described above, after the signal outputted by the liquid level sensor 155 changes to the high level signal, the ink amount Vs is equal to the current total ink amount Vt. The ink amount Vc is equal to zero.

Subsequent to step S51, the controller 130 displays both of the calculated current ink amounts Vc and Vs or the calculated current total ink amount Vt on the display 17 (e.g., step S52). After the signal outputted by the liquid level sensor 155 changes to the high level signal, the ink amount Vc is equal to zero. Therefore, the controller 130 does not overwrite the ink amount Vc currently stored in the IC board 247 of the cartridge 200 with the newly calculated ink amount Vc.

Subsequent to step S42, the controller 130 compares the count value SN updated in step S50 and the threshold N_{th} (e.g., step S53). If the controller 130 determines that the count value SN updated in step S50 is less than the threshold N_{th} (e.g., NO in step S53), the controller 130 ends the count processing. If the controller 130 determines that the count value SN updated in step S50 is greater than or equal to the threshold N_{th} (e.g., YES in step S53), the controller 130

assigns the value “ON” to the S_Empty flag (e.g., step S54). Thereafter, the controller 130 determines that at least one of the S_Empty flags is assigned with the value “ON”, the controller 130 prohibits ink discharge through the head 21 and ends the count processing.

If the controller 130 determines that both of the information indicating the signal received from the liquid level sensor 155 stored in the RAM 133 in step S23 and the information indicating the signal received from the liquid level sensor 155 stored in the RAM 133 in step S25 indicate the high level signal (L) (e.g., H to H in step S41), the controller 130 reads the count value SN stored in the EEPROM 134. Thereafter, the controller 130 adds, to the read count value SN, the value corresponding the ink amount for discharge instructed immediately before step S24, and stores the updated count value SN in the EEPROM 134. That is, the controller 130 updates the count value SN (e.g., step S50). The controller 130 also updates the count value TN. Subsequent to step S50, the controller 130 executes steps S51 to S54 using the count value SN updated in step S40.

Effects

According to the illustrative embodiment, in response to receipt of the low level signal from the installation sensor 154 after the controller 130 receives the low level signal from the installation sensor 154 and before the elapsed time T exceeds the corrected specification time ST, the controller 130 may close the S_Empty notification screen.

In response to receipt of the low level signal from the installation sensor 154, the controller 130 may display the ink refilling notification screen on the display 17. In response to the elapsed time T having exceeded the corrected specified time ST, the controller 130 may display the S_Empty notification screen again on the display 17. The controller 130 determines how much time has elapsed (e.g., the elapsed time T) with respect to a specified time ST appropriately determined based on the type information of the newly-attached cartridge 200 and the signal outputted by the temperature sensor 89. Thus, the controller 130 may accurately determine whether ink flow from the cartridge 200 into the tank 160 has resulted sufficient ink in the tank 160.

ALTERNATIVE EMBODIMENTS

In the illustrative embodiment, in response to receipt of the low level signal from the installation sensor 154, the controller 130 closes the S_Empty notification screen and displays the ink refilling notification screen on the display 17. Nevertheless, in other embodiments, for example, in response to receipt of the low level signal from the installation sensor 154, the controller 130 may continue displaying the S_Empty notification screen without displaying the ink refilling notification screen. In still other embodiments, for example, in response to receipt of the low level signal from the installation sensor 154, the controller 130 may close the S_Empty notification screen instead of displaying the ink refilling notification screen. That is, none of the S_Empty notification screen and the ink refilling notification screen may be displayed on the display 17 at that time. In either of the cases where the controller 130 continues displaying the S_Empty notification screen without displaying the ink refilling notification screen or where the controller 130 closes the S_Empty notification screen without displaying the ink refilling notification screen, it may be preferable that, in response to the elapsed time T having exceeded the corrected specified time ST (e.g., YES in step

S18), the controller 130 display the S_Empty notification screen again on the display 17. In the example cases, displaying the S_Empty notification screen on the display 17 is an example of causing the notification device to provide a second alert.

In the illustrative embodiment, in a case where all of the four S_Empty flags are assigned with the value “OFF”, the controller 130 allows the head 21 to discharge ink.

Thus, when a user replaces at least one cartridge 200 with a new one 200 in response to displaying of the C_Empty notification screen while all of the four S_Empty flags are assigned with the value “OFF”, the controller 130 allows ink discharge through the head 21. In other embodiments, for example, in response to replacement of the at least one cartridge 200, that is, in response to determining that the controller 130 has received the low level signal, the high level signal, and the low level signal in this order from the installation sensor 154, the controller 130 may prohibit ink discharge through the head 21. In such a case, in response to determining that the controller 130 has received the low level signal from the liquid level sensor 155 due to ink flow from the cartridge 200 to the tank 160, the controller 130 may allow ink discharge through the head 21.

In the illustrative embodiment, the controller 130 corrects the specified time ST based on the temperature t detected by the temperature sensor 89 (e.g., step S18). Higher temperature may cause lower viscosity of ink, thereby increasing the speed of ink flow from the cartridge 200 to the tank 160. Increase in the ink flow speed may shorten the time required for the ink flow from the cartridge 200 to the tank 160 as compared with the time required by ink of the same volume having higher viscosity to flow from the cartridge 200 to the tank 160. Consequently, it may be preferable that the specified time ST be corrected such that the corrected specified time ST is shorter as the temperature t is higher.

Nevertheless, in other embodiments, the specified time ST may be corrected based on another factor. In one example, the specified time ST may be corrected based on the ink viscosity. Higher ink viscosity may cause lower speed of ink flow from the cartridge 200 to the tank 160. Consequently, it may be preferable that the specified time ST be corrected such that the corrected specified time ST is shorter as the temperature t is higher. In such a case, the controller 130 may correct the specified time ST stored in the RAM 18 based on information indicating the ink viscosity stored in the memory of the IC board 247 of the newly-attached cartridge 200 (e.g., step S18).

In another example, the specified time ST may be corrected based on the surface level of ink stored in the liquid chamber 210 of the cartridge 200. Higher surface level of ink may cause higher speed of ink flow from the cartridge 200 to the tank 160. Consequently, it may be preferable that the specified time ST be corrected such that the corrected specified time ST is shorter as the surface level of ink is higher. In such a case, the controller 130 may correct the specified time ST stored in the RAM 18 based on information indicating the surface level of ink stored in the liquid chamber 210 stored in the memory of the IC board 247 of the newly-attached cartridge 200 (e.g., step S18).

In still another example, the specified time ST may be corrected based on a channel resistance Rc of the newly-attached cartridge 200. The channel resistance Rc may be resistance caused when air passes through a semipermeable membrane positioned in the channel extending from the ventilation opening 221 to the through hole 218 in the cassette 200. Higher channel resistance Rc may cause lower speed of ink flow from the cartridge 200 to the tank 160.

Consequently, it may be preferable that the specified time ST be corrected such that the corrected specified time ST is longer as the channel resistance R_c is higher. In such a case, the controller 130 may correct the specified time ST stored in the RAM 18 based on information indicating the channel resistance R_c stored in the memory of the IC board 247 of the newly-attached cartridge 200 (e.g., step S18).

In the illustrative embodiment, if the controller 130 determines that the controller 130 has received the low level signal, the high level signal, and the low level signal in this order from the installation sensor 154 (e.g., YES in step S14), the controller 130 executes step 15. That is, in response to attachment of a cartridge 200 to a corresponding vacant space of the installation case 150, the controller executes step S15. In other words, if the controller 130 determines that attachment of a cartridge 200 to a corresponding vacant space of the installation case 150 has been completed, the controller 130 may execute step S55. Determining that the controller 130 has received the low level signal, the high level signal, and the low level signal in this order from the installation sensor 154 is an example of determining that attachment of a cartridge to the installation case 150 has been completed, i.e., determining that the cartridge is located at the particular position. Another example of determining that attachment of a cartridge 200 to the installation case 150 has been completed will be described.

In one example, the controller 130 receives the low level signal after receiving the high level signal from the cover sensor 88. Then, the controller 130 reads the identifying information from the memory of the IC board 247 of the newly-attached cartridge 200 and compares the read identifying information of the newly-attached cartridge 200 with the identifying information of the previously-used cartridge 200 stored in the EEPROM 134. If the controller 130 determines that the identifying information read from the memory of the IC board 247 is different from the identifying information stored in the EEPROM 134, the controller 130 may execute step S35. That is, the disclosure "the controller 130 reads the identifying information from the memory of the IC board 247 of the newly-attached cartridge 200 and compares the read identifying information with the identifying information of the previously-used cartridge 200 stored in the EEPROM 134. As a comparison result, the controller 130 determines that the identifying information read from the memory of the IC board 247 is different from the identifying information stored in the EEPROM 134." is another example of determining that attachment of a cartridge 200 to the installation case 150 has been completed.

In another example, the controller 130 may receive the low level signal after receiving the high level signal from the cover sensor 88. The controller 130 may display, on the display 17, a confirmation screen asking the user whether attachment of a cartridge 200 to the installation case 150 has been completed. While the controller 130 displays the confirmation screen on the display 17, the controller 130 may receive an input onto the confirmation screen via the operation panel 22. If the controller 130 determines that the received input corresponds to completion of the attachment of a cartridge 200 to the installation case 150, the controller may execute step S35. That is, the disclosure "the controller 130 receives the low level signal after receiving the high level signal from the cover sensor 88. The controller 130 displays, on the display 17, a confirmation screen asking the user whether attachment of a cartridge 200 to the installation case 150 has been completed. While the controller 130 displays the confirmation screen on the display 17, the

controller 130 receives an input onto the confirmation screen via the operation panel 22. The received input corresponds to completion of the attachment of a cartridge 200 to the installation case 150" is another example of determining that attachment of a cartridge 200 to the installation case 150 has been completed.

In the illustrative embodiment, the ink supply port 234 of the supply tube 230 and the opening 183 of the needle 181 are opened, thereby providing communication between the ink valve chamber 213 of the supply tube 230 and the internal space of the needle 181. Nevertheless, in other embodiments, for example, each cartridge 200 may have the ink supply port 234 in the rear wall 202. In such a case, for example, the ink supply port 234 may be a through hole that may penetrate the rear wall 202 in a thickness direction of the rear wall 202. The internal space of the ink supply port 234 is another example of the channel whose one end communicates with the liquid chamber 210 and whose other end communicates with the outside of the printer 200. In this case, during attachment of the cartridge 200 to the installation case 150, the needle 181 may enter the liquid chamber 210 of the cartridge 200 via the ink supply port 234 and one end (e.g., the opening 183) of the needle 181 may be positioned in the liquid chamber 210 of the cartridge 200. This may allow communication between the liquid chamber 210 of the cartridge 200 and the internal space of the needle 180. That is, in a state where the cartridge 200 is fully attached to the installation case 150, the internal space of the needle 181 may constitute a channel that may provide communication between the liquid chamber 210 of the cartridge 200 and the liquid chamber 171 of the tank 160.

In other embodiments, for example, each cartridge 160 may have the opening 183 in the front wall 162. In such a case, for example, the opening 183 may be a through hole that may penetrate the front wall 162 in a thickness direction of the front wall 162. The internal space of the opening 183 is another example of the channel whose one end communicates with the liquid chamber 210 and whose other end communicates with the outside of the printer 200. In this case, during attachment of the cartridge 200 to the installation case 150, the supply tube 230 may enter the liquid chamber 171 of the tank 160 via the opening 183 and the other end (e.g., the ink supply port 234) of the supply tube 230 may be positioned in the liquid chamber 171 of the tank 160. This may allow communication between the liquid chamber 210 of the cartridge 200 and the internal space of the needle 180. That is, in a state where the cartridge 200 is fully attached to the installation case 150, the ink valve chamber 213 may constitute a channel that may provide communication between the liquid chamber 210 of the cartridge 200 and the liquid chamber 171 of the tank 160.

In the illustrative embodiment, the controller 130 determines, based on the type of the signal outputted by the liquid level sensor 155, whether the detection portion 194 of the actuator 190 is located at the detection position. Nevertheless, the configuration of the liquid level sensor 155 is not limited to the specific example as long as the liquid level sensor 155 can detect the surface level of ink stored in the liquid chamber 171. In one example, the liquid level sensor 155 may be a sensor configured to optically detect the surface level of ink stored in the liquid chamber 171 using prisms having different reflectivity depending on whether ink contacts the rear wall 164 of the liquid chamber 171. In another example, the surface level of the ink stored in the liquid chamber 171 may be detected by an electrode.

In the illustrative embodiment, in a case where at least one of the four S_Empty flags is assigned with the value "ON"

31

(e.g., ON in step S11), the controller 130 prohibits all of the four tanks 160 from discharging ink through the head 21. Nevertheless, in other embodiments, for example, in a case where at least one of the four S_Empty flags is assigned with the value “ON”, the controller 130 may prohibit only the tank 160 corresponding to the S_Empty flag assigned with the value “ON” from discharging ink through the head 21. In still other embodiments, for example, in a case where at least one of the S_Empty flags for magenta, cyan, and yellow tanks 160 is assigned with the value “ON” and the S_Empty flag for the black tank 160 is assigned with the value “OFF”, the controller 130 may prohibit all of the magenta, cyan, and yellow tanks 160 from discharging ink through the head 21 but allow the black tank 160 to discharge ink through the head 21.

The IC board 247 is configured to contact the contact 152 to be electrically connected to the contact 152. Nevertheless, in other embodiments, for example, an information medium and an interface may be used instead. In such a case, data may be written and read using radio waves such as Near Field Communication (“NFC”) or Radio Frequency Identification.

In the illustrative embodiment, ink is an example of the liquid. Nevertheless, in other embodiments, for example, the liquid may be a pre-treatment liquid that may be ejected onto a sheet prior to ink ejection or water that may be used for cleaning the head 21.

What is claimed is:

1. A liquid discharge apparatus comprising:
an installation case configured to accommodate a cartridge including a cartridge channel and a cartridge chamber;
a tank including a chamber, the tank further including:
a first channel including one end in fluid communication with an outside of the tank and an opposite end in fluid communication with the chamber;
a second channel including one end positioned below the first channel and in fluid communication with the chamber; and
a third channel including one end in fluid communication with the chamber and the other end communicated with the outside of the tank;
a head in fluid communication with an opposite end of the second channel from the one end;
a liquid level sensor;
a notification device; and
a controller,
wherein the cartridge chamber is in fluid communication with the chamber of the tank via at least one of the cartridge channel and the first channel while the cartridge is located at a particular position in the installation case, and
wherein the controller is configured to:
receive a first signal from the liquid level sensor, the first signal being outputted from the liquid level sensor if a surface level of liquid in the chamber is lower than a predetermined level;
in response to the receipt of the first signal, cause the notification device to provide a first alert;
determine whether the cartridge is located at the particular position in the installation case;
receive a second signal from the liquid level sensor, the second signal being outputted if the surface level of liquid in the chamber is higher than or equal to the predetermined level; and
in response to the receipt of the second signal from the liquid level sensor after determining that the car-

32

tridge is located at the particular position in the installation case, clear the first alert.

2. The liquid discharge apparatus according to claim 1, wherein the controller is configured to:

- 5 receive a discharge instruction for discharging liquid through the head;
determine a count value corresponding to a liquid amount based on the discharge instruction that has been received after receiving the first signal;
determine whether the count value has reached a threshold; and
based on determining that the count value has reached the threshold, cause the notification device to provide the first alert.

3. The liquid discharge apparatus according to claim 1, wherein the controller is configured to:

- 15 in response to the receipt of the first signal, prohibit liquid discharge through the head; and
in response to the receipt of the second signal from the liquid level sensor after determining that the cartridge is located at the particular position in the installation case, clear the prohibition of liquid discharge through the head.

4. The liquid discharge apparatus according to claim 1, wherein the controller is configured to, in response to absence of the second signal from the liquid level sensor before the controller determines that an elapsed time has exceeded a specified time since the controller determined that the cartridge is located at the particular position in the installation case, cause the notification device to provide a second alert.

5. The liquid discharge apparatus according to claim 1, wherein the controller is configured to:

- 25 based on the determination that the cartridge is located at the particular position in the installation case, cause the notification device to provide a third alert; and
in response to the receipt of the second signal from the liquid level sensor being absent before the controller determines that an elapsed time has exceeded a specified time since the controller determined that the cartridge is located at the particular position in the installation case has been completed, cause the notification device to provide a fourth alert.

6. The liquid discharge apparatus according to claim 4, further comprising an interface,

- 35 wherein the installation case is configured to accommodate one of different types of cartridges, and
wherein the controller is configured to, based on the determination that the one of the different types of cartridges is located at the particular position in the installation case, read cartridge information indicating a type of the accommodated cartridge, from a memory of the accommodated cartridge through the interface; and
determine whether the elapsed time has exceeded the specified time, the specified time being determined based on the read cartridge information.

7. The liquid discharge apparatus according to claim 4, further comprising an interface,

- 40 wherein the installation case is configured to accommodate one of different types of cartridges, and
wherein the controller is configured to, based on the determination that the one of the different types of cartridges is located at the particular position in the installation case, read cartridge information indicating

33

- viscosity of liquid in the cartridge chamber, from a memory of the accommodated cartridge through the interface; and
- determine whether the elapsed time has exceeded the specified time, the specified time being determined based on the read cartridge information.
8. The liquid discharge apparatus according to claim 4, further comprising an interface, wherein the installation case is configured to accommodate one of different types of cartridges, and wherein the controller is configured to, based on the determination that the one of the different types of cartridge is located at the particular position in the installation case, read cartridge information indicating a surface level of liquid in the cartridge chamber, from a memory of the accommodated cartridge through the interface; and
- determine whether the elapsed time has exceeded the specified time, the specified time being determined based on the read cartridge information.
9. The liquid discharge apparatus according to claim 4, further comprising an interface, wherein the installation case is configured to accommodate one of different types cartridges, and wherein the controller is configured to, based on the determination that the one of the different types of cartridges is located at the particular position in the installation case, read cartridge information indicating a channel resistance of the accommodated cartridge, from a memory of the accommodated cartridge through the interface; and
- determine whether the elapsed time has exceeded the specified time, the specified time being determined based on the read cartridge information.
10. The liquid discharge apparatus according to claim 4, further comprising a temperature sensor, wherein the controller is configured to:
- receive a signal from the temperature sensor, the signal outputted responsive to ambient temperature; and
  - determine whether the elapsed time has exceeded the specified time, the specified time being determined based on the signal received from the temperature sensor.
11. The liquid discharge apparatus according to claim 1, further comprising the cartridge.
12. A liquid discharge apparatus comprising:
- an installation case configured to accommodate a cartridge including a cartridge channel and a cartridge chamber;
  - a tank including a chamber, the tank further including:
  - a first channel including one end in fluid communication with an outside of the tank and an opposite end in fluid communication with the chamber;

34

- a second channel including one end positioned below the first channel and in fluid communication with the chamber; and
- a third channel including one end in fluid communication with the chamber and the other end communicated with the outside of the tank;
- a head in fluid communication with an opposite end of the second channel from the one end;
- a liquid level sensor; and
- a controller,
- wherein the cartridge chamber is in fluid communication with the chamber of the tank via at least one of the cartridge channel and the first channel while the cartridge is located at a particular position in the installation case, and
- wherein the controller is configured to:
- receive a first signal from the liquid level sensor, the first signal being outputted from the liquid level sensor if a surface level of liquid in the chamber is lower than a predetermined level;
  - in response to the receipt of the first signal, prohibit liquid discharge through the head;
  - determine whether the cartridge is located at the particular position in the installation case;
  - receive a second signal from the liquid level sensor, the second signal being outputted if the surface level of liquid in the chamber is higher than or equal to the predetermined level; and
  - in response to the receipt of the second signal from the liquid level sensor after determining that the cartridge is located at the particular position in the installation case, allow the liquid discharge through the head.
13. The liquid discharge apparatus according to claim 12, further comprising a notification device, wherein the controller is configured to:
- in response to the receipt of the first signal, cause the notification device to provide a first alert; and
  - in response to the receipt of the second signal from the liquid level sensor after determining that the cartridge is located at the particular position in the installation case, clear the first alert.
14. The liquid discharge apparatus according to claim 12, wherein the controller is configured to, based on the determination that the cartridge is located at the particular position in the installation case, prohibit the liquid discharge through the head until the controller determines that the second signal has been received.
15. The liquid discharge apparatus according to claim 12, further comprising the cartridge.
